DESIGN FOR A PIN

Alfred Benjamin Shawl, New York, N. Y.

Application July 19, 1944, Serial No. 114,457

Term of patent 3½ years

(Cl. D45—19)

To all whom it may concern:

Be it known that I, Alfred Benjamin Shawl, native of Poland and citizen of no country, residing at New York, N. Y., in the county of New York and State of New York, have invented a new, original, and ornamental Design for a Pin, of which the following is a specification, reference being had to the accompanying drawing, forming part thereof.

In the drawing

Fig. 1 is a front view of a pin showing my new design;

Fig. 2 is a rear view of the pin.

I claim:

The ornamental design for a pin, as shown.

ALFRED BENJAMIN SHAWL.
